HILAND R. FARNSWORTH, OF SANDUSKY, OHIO, ASSIGNOR TO THE PAPER & TEXTILE MACHINERY COMPANY, OF SANDUSKY, OHIO

WIRE GUIDE

Application filed November 22, 1928. Serial No. 321,170.

The invention to be hereinafter described relates to wire guides for paper making machines.

While the present invention has been designed with particular thought of its application to machines in which the wire travels vertically or in a place at a considerable angle to the vertical in contradistinction to the standard machine now in use and in which the wire travels in a plane approximating the horizontal, it will be readily understood that it may also be applied to and used on such standard machines. And it is not my intention to limit the application of the invention to vertical wire type.

A continual and very serious trouble with paper making machines is the tendency of wires to crawl toward one side or the other of the machine. A very slight lateral travel brings the edge of the wire into rubbing contact with stationary parts, carries a part of the wire and its paper web outside of or beyond the effective suction area of the couch roll, delivers the sheet more toward one side of the felt than it should, and has various other objections. As soon as the edge, by rubbing, gets rough there are a number of other serious well known objections which arise.

There are several types of wire guides, in general use at present and giving a certain degree of satisfaction. These guides, however, are, naturally, designed for use on the standard horizontal-wire type of machine and are incapable of use on the vertical-wire type. Their very construction and mode of operation make it impossible to apply them to such different type of machine.

The main objects of the present invention are to provide a wire guide particularly applicable to the vertical-wire type of paper making machine; and a guide of simple, efficient and compact construction, having the least number of parts practicable and as nearly absolutely reliable as possible under any and all average working conditions at all likely to be encountered.

A further object is to provide a guide which may be operated both manually and automatically and in either manner independently of the other, as may be desired.

In order to disclose the construction, operation and use of the invention, reference should be had to the accompanying drawings forming part of the present application. Throughout the several figures of the drawings like reference characters designate the same parts in the several different views.

In the drawings:—

Fig. 1 is a diagrammatic front elevation of one wire of a vertical-wire machine with the invention applied;

Fig. 2 is an enlarged top plan view of one end of the guide roll, its mounting, and the invention applied; and

Fig. 3 is an end view of Fig. 2, showing the invention in elevation, partly broken away.

The guide roll, as its name denotes, is intended to direct or guide the wire in the right or true path—to make it run accurately in the machine, as it should. Consequently, there must be means for controlling its operation or for regulating its effect. It is well known that a revolving cylindrical roll will have no direction-changing effect on the felt, sheet, wire, or like member passing over and bearing on its surface, as long as the axis of rotation of the roll is at right angles to the direction of travel of such member. It is also well known that as soon as the axis is inclined even very slightly, relatively to the perpendicular, there will be an immediate pronounced lateral feeding action by the roll, very much in the nature of the feeding action of a spiral conveyor. Or, as it is often put, the wire will crawl in the direction of the side of the machine toward which the guide roll is inclined. And the greater the incline of the guide roll the greater and more pronounced the crawl. And so, it has become customary, in the horizontal-wire type of machine, to regulate the wire, in its lateral crawl, by moving the guide roll—inclining it more or less, relatively to the perpendicular to the path of travel of the making wire. In fast running machines such as are universally used today, an almost infinitesimal lateral movement in one entire length of a making wire, is so rapidly multiplied that the total permissible lateral crawl is so quickly exceeded that the wire is injured or other serious

damage done before it can be stopped. In various attempts to overcome these objections, on the horizontal-wire type machine, different automatic means have been devised for inclining the axis of the roll. Those at present in most general use are automatic and actuated by the wire. They are all applied to and operable only with the horizontal-wire type of machine.

- 10 The present invention on the other hand is designed, constructed and operable for and with the vertically travelling wire of a vertical-wire type machine, such as is not in commercial use at the present time.
- 15 Referring to the drawings in detail 1 indicates the guide roll having one end mounted in a relatively stationary bearing but with sufficient "play" to permit the roll to be inclined in one direction on the other for guiding purposes, all as in well known practice. It is, of course, driven by the engaging making wire 2 in usual and well known manner, as in the horizontal-wire type machine, as will be evident on reference to Figs. 1 and 2.
- 20 The opposite end of roll 1 is journaled in one end of a plate, bar or carrying arm 3. The opposite end of arm 3 is keyed, splined, or otherwise suitably rigidly removably fastened to a tubular shaft 4 to rotate or rock therewith but not relatively thereto. This shaft is mounted for free rotation in suitable brackets on the machine frame and at a suitable point slightly spaced from arm 3 has secured thereto in the same manner as the connection 25 between shaft 4 and arm 3, one end of the head of a T-lever arm 5 which arm extends in a direction opposite to arm 3. Preferably arm 5 is formed as T-shaped, for purposes to be later disclosed. It will be seen that the 30 arms 3 and 5 and tubular shaft 4 constitute an elbow lever in one end of which is revolvably mounted the movable end of the guide roll, the fulcrum being shaft 4. To counterbalance the weight of the roll end and maintain it in free running operative position a 35 suitable weight 6 is provided. This weight is adjustably mounted on the arm in any usual and well known manner, which need not be further disclosed.
- 40 The roll being in continual running contact with the making wire will be driven thereby continually and at approximately the same rate as said wire. This continual rotation is utilized in operating the wire guide of this 45 invention, as will be understood by those familiar with the standard wire guides now in general use on the horizontal-wire type of machine. In this invention, a sprocket wheel 7 is made fast on the end of the spindle of 50 roll 1 and through a sprocket chain 8 drives a second sprocket wheel 9 which is keyed to the stub shaft 4', journaled in a tubular shaft 4. Sprocket 9 in driving shaft 4' also drives an eccentric which is made fast thereto and 55 which carries a small wrist pin 10 on which

is journaled the upper end or stem of a fork 11 which carries oppositely acting dogs or pawls adapted to selectively engage cooperating oppositely disposed ratchets on the ratchet disc 12 which is fixed to one end of a rod 13 which journaled in the machine frame and threaded through the lower or free end 5' of the T-lever arm. A suitable stop nut on collar 14 fixed to rod 13 keeps it in place in the frame. As sprocket 9 is kept in continual rotation by chain 8 the Y-fork will be in continual reciprocation. As long as neither dog of the fork engages the ratchet disc the rod 13 will remain stationary and the lever 3, 4, 5, 5' will not actuate the guide roll. But as soon as either dog does so engage its cooperating ratchet the rod and its connections will be actuated and the free end of the guide roll 1 will be actuated to change the inclination to correct the crawl of the wire.

To effect engagement of the actuating pawls a well known type of wire guide mechanism is combined with the construction hereinbefore described. This well known mechanism will be set forth only briefly, as its construction and operation are well known in its use on the standard horizontal-wire machines. It is what is known in the art as a one-palm guide, that term designating a guide in which a single wire engaging means controls the guide in contradistinction to those guides in which two engaging means operate from opposite sides. Thus, a single palm or plate 15 is carried on the upper end of a bar 16 which is flexibly and yieldingly held in operative contact by a coil spring 17. The palm is adapted when in operative position, to bear very lightly on the edge of the making wire and to follow any lateral or crawling movement of it. This well known guide mechanism is installed, of course, with the wire and guide roll in their respective correct operative positions, the guide roll having its longitudinal axis at right angles to the length of the wire. The palm will then just contact with the wire edge and the arm carrying it will be substantially at right angles to the plane of the making wire. Through a rockable crank shaft 19, the arm or bar 16 operates crank arm 20 at the opposite end of 19. This crank is connected by a link rod 21 to one branch of the Y or fork 11. So, it will be evident that this train of connections will throw one or the other dog into engagement with its respective ratchet according to the direction of lateral travel of the wire but will maintain them in neutral or inoperative position as long as the wire is in proper position.

From the above it will be seen as soon as the wire starts to crawl from its true and right path the proper dog will be brought into engagement with its cooperating ratchet thereby actuating the rod 13 in the right direction to cause operation of the lever train

in the right direction to effect that inclination of the guide roll 1 which will return the wire or move it in the opposite direction to offset the previous crawl.

- 5 The outer free end of the rod 13 is provided with a hand wheel or like manual operation means 22 so that the roll 1 may be inclined by hand instead of automatically, if desired. It is only necessary to move the 10 dogs to inoperative position and then operate rod 13 by hand wheel 22 until the roll 1 has been moved to the position to return the wire, as will be readily understood.

The slight arcuate movement of the roll 15 end will not in any practical sense affect contact with the wire either as to driving the roll or as to guiding the wire.

Many changes may be made in the construction, arrangement and disposition of the 20 various parts of the invention within the scope of the appended claims without in any degree departing from the field of the invention and it is meant to include all such within this application wherein only a single illustrative construction has been disclosed for 25 purposes of explanation.

Having described my invention, what I claim and desire to protect by Letters Patent is:—

30 1. A wire guide for paper machines comprising an adjustably movable guide roll over which a wire travels, a stationary frame, a movable support for an end of said roll comprising a lever arm pivotally supported upon said stationary frame, and means driven by the roll for pivotally moving said 35 lever arm to change the axial inclination of the roll with respect to the direction of travel of the wire.

40 2. A wire guide for paper machines comprising a roll over which a wire travels and is adapted to be engaged thereby in surface contact, a stationary frame, a movable support for an end of said roll comprising a lever 45 arm pivotally supported on said stationary frame, means driven from said roll for pivotally moving the lever arm to change the axial inclination of the roll with respect to the direction of travel of the wire, and means 50 responsive to lateral movement of the wire for actuating said lever moving means.

3. A wire guide for paper machines comprising a roll over which a wire travels, a stationary frame, a movable support for an 55 end of said roll comprising a lever arm pivotally supported upon said stationary frame, a counter weight on said lever arm positioned from the lever fulcrum in a direction opposite to the point of attachment of the roll, and means driven by the wire for pivotally moving said lever arm to change the axial inclination of the roll with respect to the direction 60 of travel of the wire.

4. A wire guide for paper machines comprising a roll over which a wire travels, a 65

stationary frame, a movable support for an end of said roll comprising a lever arm pivotally supported upon said stationary frame, means driven from the wire and automatically actuated upon lateral movement of the 70 wire for pivotally moving said lever arm, and manual means operable independently of said automatically actuated means for pivotally moving the lever arm.

5. A wire guide for paper machines comprising a roll over which a wire travels, a stationary frame, a movable support for an end of said roll comprising a lever arm pivotally supported upon said stationary frame, means for pivotally moving the supporting lever upon lateral movement of the wire, said means comprising a pawl mechanism driven from the roll, a ratchet mechanism operable by the pawl mechanism, means connecting the lever to the ratchet mechanism for movement thereof upon movement of the ratchet mechanism, and means in contacting engagement with the wire to move the pawl mechanism into operating engagement with the ratchet mechanism.

6. A wire guide for paper machines comprising a roll over which a wire travels, a stationary frame, a movable support for an end of said roll comprising a lever arm pivotally supported on said stationary frame upon an axis parallel to the normal position of the roll axis, a mechanism operable upon lateral movement of the wire to pivotally move the roll supporting lever, said mechanism comprising a rotatable member positioned coaxially with the lever pivot, and means for driving said rotatable member from the roll.

7. A wire guide for paper machines comprising a roll over which a wire travels, a stationary frame, a movable support at an end of said roll comprising a lever arm pivotally supported upon said stationary frame, a counter weight on said lever arm positioned from the lever fulcrum in a direction opposite to the point of attachment of the roll, means for pivotally moving the supporting lever upon lateral movement of the wire, said means comprising a pawl mechanism driven by the roll, a ratchet mechanism operable by the pawl mechanism, means connecting the lever to the ratchet mechanism for actuation upon movement of the ratchet mechanism, and means in contacting engagement with the wire to move the pawl mechanism into operating engagement with the ratchet mechanism.

8. A wire guide for paper machines comprising an adjustably movable guide roll over which a wire travels, a support for an 125 end of said roll movable in a curved path defined as an arc of a circle, mechanism for moving said roll support in accordance with lateral movement of the wire, said mechanism comprising a rotatable member mounted on

axially with the center of curvature of the path of movement of the roll support, and means for driving said rotatable member by rotation of said roll.

5 9. A wire guide for paper machines comprising an adjustably movable guide roll over which a wire travels, a support for an end of said roll movable in a curved path defined as an arc of a circle, mechanism for moving 10 said roll support in accordance with lateral movement of the wire, said mechanism comprising a rotatable member mounted coaxially with the center of curvature of the path of movement of the roll support, means for 15 driving said rotatable member by rotation of said roll, and means on said support for counterbalancing the weight of the roll sustained by said support.

In testimony whereof I affix my signature.
